FIG. 6 is a front view thereof;

FIG. 7 is a perspective view of a fourth embodiment of a gemstone and charm for a necklace or bracelet;

FIG. 8 is a front view thereof;

FIG. 9 is a perspective view of a fifth embodiment of a gemstone and charm for a necklace or bracelet;

FIG. 10 is a front view thereof;

FIG. 11 is a perspective view of a sixth embodiment of a gemstone and charm for a necklace or bracelet;

FIG. 12 is a front view thereof;

FIG. 13 is a perspective view of a seventh embodiment of a gemstone and charm for a necklace or bracelet;

FIG. 14 is a front view thereof;

FIG. 15 is a perspective view of an eighth embodiment of a gemstone and charm for a necklace or bracelet;

FIG. 16 is a front view thereof;

FIG. 17 is a perspective view of a ninth embodiment of a gemstone and charm for a necklace or bracelet;

FIG. 18 is a front view thereof;

FIG. 19 is a perspective view of a tenth embodiment of a gemstone and charm for a necklace or bracelet;

FIG. 20 is a front view thereof;

FIG. 21 is a perspective view of an eleventh embodiment of a gemstone and charm for a necklace or bracelet;

FIG. 22 is a front view thereof;

FIG. 23 is a perspective view of a twelfth embodiment of a gemstone and charm for a necklace or bracelet;

(Continued)

FIG. 24 is a front view thereof;
 FIG. 25 is a perspective view of a thirteenth embodiment of a gemstone and charm for a necklace or bracelet;
 FIG. 26 is a front view thereof;
 FIG. 27 is a perspective view of a fourteenth embodiment of a gemstone and charm for a necklace or bracelet;
 FIG. 28 is a front view thereof;
 FIG. 29 is a perspective view of a fifteenth embodiment of a gemstone and charm for a necklace or bracelet;
 FIG. 30 is a front view thereof;
 FIG. 31 is a perspective view of a sixteenth embodiment of a gemstone and charm for a necklace or bracelet;
 FIG. 32 is a front view thereof;
 FIG. 33 is a perspective view of a seventeenth embodiment of a gemstone and charm for a necklace or bracelet;
 FIG. 34 is a front view thereof;
 FIG. 35 is a perspective view of an eighteenth embodiment of a gemstone and charm for a necklace or bracelet;
 FIG. 36 is a front view thereof;
 FIG. 37 is a perspective view of a nineteenth embodiment of a gemstone and charm for a necklace or bracelet;
 FIG. 38 is a front view thereof;
 FIG. 39 is a perspective view of a twentieth embodiment of a gemstone and charm for a necklace or bracelet;
 FIG. 40 is a front view thereof;
 FIG. 41 is a perspective view of a twenty-first embodiment of a gemstone and charm for a necklace or bracelet;
 FIG. 42 is a front view thereof;
 FIG. 43 is a perspective view of a twenty-second embodiment of a gemstone and charm for a necklace or bracelet;
 FIG. 44 is a front view thereof;
 FIG. 45 is a perspective view of a twenty-third embodiment of a gemstone and charm for a necklace or bracelet;
 FIG. 46 is a front view thereof;
 FIG. 47 is a perspective view of a twenty-fourth embodiment of a gemstone and charm for a necklace or bracelet;
 FIG. 48 is a front view thereof;
 FIG. 49 is a perspective view of a twenty-fifth embodiment of a gemstone and charm for a necklace or bracelet; and,
 FIG. 50 is a front view thereof.
